[57] **CLAIM**

The ornamental design for a lock bolt cover plate, as
shown and described.

DESCRIPTION

FIG. 1 is a front perspective view of a lock bolt cover
plate showing my new design;

FIG. 2 is a bottom, rear perspective view thereof;

FIG. 3 is a side elevational view thereof, the opposite
side being substantially a mirror image of that shown;

FIG. 4 is a top plan view thereof; and

FIG. 5 is a rear elevational view thereof.
